LOCK

Willard Mathes, Terryville, Conn., assignor to
Eagle Lock Co., New York, N. Y., a corporation
of Connecticut

Application May 9, 1936, Serial No. 78,793

7 Claims. (Cl. 70—25)

My invention relates to locks and has special reference to combination padlocks.

One of the objects of my invention is to provide a padlock which is of simple and inexpensive construction, and in which the shackle is so held as to withstand severe strains without danger of injury to the operating parts of the lock.

Another object of the invention is to provide a combination padlock having novel and improved means for ensuring proper locking of the shackle upon insertion thereof and for preventing derangement of parts when the shackle is withdrawn.

The several features of the invention whereby the above-mentioned and other objects may be attained will be readily understood from the following description and accompanying drawings, in which:

Figure 1 is a front view of a padlock embodying features of my invention in their preferred form;

Fig. 2 is a sectional elevation, on an enlarged scale, taken on the line 2—2 of Fig. 1;

Figs. 3 and 4 are sectional elevations, respectively taken on the lines 3—3 and 4—4 of Fig. 2;

Fig. 5 is a view similar to Fig. 4, but showing certain parts in a different position; and

Figs. 6, 7 and 8 are sectional elevations, respectively taken on the lines 6—6, 7—7 and 8—8 of Fig. 3.

My improved lock as illustrated in the drawings, is in the form of a combination padlock having a lock-case 2, sliding shackle 4, a bolt 6, and tumbler mechanism comprising disks 8 having slots or gatings 10 and lugs or pins 12. The tumbler disks 8 are mounted on the usual central stud 14 riveted to the rear side of the casing, and the disks are adapted to be operated by means of the usual dial carrying knob 16 mounted on the front of the casing. A coiled spring 15 bears against the rearmost disk 8.

In the illustrated construction, a plate 18 is secured on the rear wall of the lock case. This plate is provided with a horizontally bent apertured ear 20 through which the heel of the shackle extends. The shackle heel is provided with a projecting pin 22 which is adapted to pass through a clearance slot 24 in the ear 20 so that when the shackle is pulled outwardly the pin may pass through the slot 24, but the pin by engagement with the top side of the ear 20 prevents the shackle from being pushed in until the shackle has been turned to aline the toe thereof with the opening in the casing. The outward movement of the shackle is limited by a retainer 26 which consists of a plate having a slotted portion 28 that is received in a groove in the lower end of the heel of the shackle. The retainer 26 is guided by means of a rearwardly projecting lug 30 thereon, which is received in

a slot 32 in the backplate 18. The retainer limits the outward movement of the shackle by engagement of the slotted portion 28 thereof with the under side of the apertured ear 20.

The bolt 6 is pivoted on a pin 34 secured to the backplate 18 and the lock-case 2. The bolt is provided with an inclined surface 36 which when the shackle is moved into the lock case is engaged by an inclined surface 38 on the lower end of the toe of the shackle which turns the bolt in a direction to move a locking shoulder 40 thereon into engagement with the lower wall of a locking notch 42 in the shackle toe. The under side of the bolt 6 is provided with a downwardly projecting lug 44 which by engagement with the tumbler disks serves to hold the bolt in locking engagement with the shackle.

When the dial-knob 16 is turned to aline the gatings in the tumbler disks 8, the bolt-lug 44 is permitted to enter the gatings, as shown in Figs. 4 and 5, thus permitting the shackle to be withdrawn. The top side of the bolt is provided with a flat surface 46 which when the bolt is in locking position abuts against a horizontally bent flange 48 on the backplate 18, this flange serving to support the bolt when the bolt is in locked position.

A pawl 50 is hingedly connected with the end of the bolt 6, the pawl having a cylindrical end portion 52 which is received in a transverse socket in the end of the bolt. When the shackle is pushed into the lock case and the bolt is tipped thereby to cause it to lock with the toe of the shackle, the pawl 50 is moved outwardly and is guided by the flange 48 so as to position its end in a locking notch 54 in the heel of the shackle. The pawl is supported in locking engagement with the shackle by engagement of its upper side with the supporting flange 48.

In the illustrated construction, means is provided whereby when the bolt and pawl are moved into locking engagement with the shackle upon inward movement of the shackle, the disks are turned so as to position their gatings out of register and thus hold the bolt and pawl in locking engagement. To provide for this, a spring 56 is coiled about a pin or stud 58 on the backplate 18. One arm 60 of this spring bears against the under side of the retainer plate 26. The other arm 62 of the spring extends through a slot 63 in the retainer plate and when the bolt is in unlocked position, the end of this arm extends over a throw-pin 64 on the rear side of the rearmost tumbler disk. Upon pushing the shackle inwardly, the retainer 26 is carried therewith and it in turn by engagement with the lower arm 60 of the spring 56 turns the spring so as to cause its upper arm 62 to strike the throw-pin 64, thus turning the disk to move the gatings out of register.

From the foregoing it will be apparent that upon pushing the shackle into the casing from its unlocked position as shown in Fig. 4, the inclined surface 38 of the toe of the shackle by 5 engagement with the inclined surface 36 on the bolt 6, turns the bolt so as to position the shoulder 40 thereon into locking engagement with the notch 42 in the toe of the shackle. Such movement of the bolt also positions its top 10 surface in abutting engagement with the supporting flange 48 of the backplate 18, and causes the end of the pawl 50 to ride into the locking notch 54 in the heel of the shackle. As the bolt-lug 44 leaves the gatings in the tumbler disks 8, the 15 shackle retainer 26 through the spring 56 turns the tumbler disks so as to move the gatings out of alinement and thus hold the bolt and pawl 50 in locking engagement with the shackle.

The provision of the double locking bolt which 20 engages the heel as well as the toe of the shackle, insures the lock being capable of withstanding maximum strain on the shackle without injury to the operating parts of the lock. The provision of means for automatically moving the tumbler 25 disk gatings out of alinement upon insertion of the shackle, insures proper locking upon insertion of the shackle.

Upon withdrawal of the shackle when the disks have been turned so as to position their gatings 30 in alinement, the outward movement of the shackle serves to turn the bolt into the position shown in Fig. 4 with the bolt-lug 44 received in the gatings. This movement of the bolt simultaneously moves the pawl 50 out of engagement 35 with the locking notch 54 in the heel of the shackle. When the shackle is withdrawn, the pawl 50 by engagement with the side of the heel of the shackle holds the bolt in unlocked position with its lug 46 in the gatings in the tumblers. 40 This prevents turning of the tumblers and dial-knob, and also prevents movement of the bolt into locked position previously to insertion of the shackle.

As will be evident to those skilled in the art, 45 my invention permits various modifications without departing from the spirit thereof or the scope of the appended claims.

What I claim is:

1. In a lock, the combination of a lock case, a 50 shackle mounted to slide in the lock case, a shackle retainer for limiting the outward movement of the shackle, tumbler mechanism provided with a plurality of gatings adapted to register with each other, a bolt pivotally mounted in the 55 casing adapted when the shackle is moved into the lock case to engage the toe of the shackle, and said tumbler gatings are out of register to lock the shackle in the casing and when said gatings are in register to permit said bolt to turn 60 to release the toe of the shackle, and a device hingedly connected with the bolt acting automatically when the bolt is moved into locking engagement with the toe of the shackle to move into locking engagement with the heel portion of 65 the shackle.

2. In a lock, the combination of a lock case, a shackle mounted to slide in the lock case, a locking bolt made of two parts hingedly connected and adapted when the shackle toe is moved into 70 the lock case to be actuated by the shackle to position it in locking engagement with both the

toe and heel of the shackle, and tumbler mechanism for holding the bolt in said locking engagement with the toe and heel of the shackle and adapted to be positioned to permit release of said bolt from locking engagement with the 5 shackle.

3. In a lock, the combination of a lock case, a shackle mounted to slide in the lock case, a bolt pivotally mounted in the lock case and adapted to be engaged by the shackle when the shackle 10 is moved into the lock case so as to be moved thereby into locking engagement with the toe of the shackle, a pawl hingedly connected with the bolt so as to be moved thereby into locking engagement with the heel of the shackle, and tumbler mechanism for retaining the bolt and pawl 15 in said locking engagement with the shackle and adapted to be positioned to effect release of said bolt and pawl.

4. In a lock, the combination of a lock-case, a 20 shackle mounted to slide in the lock-case, a bolt pivotally mounted in the lock-case and adapted to interlock with the toe of the shackle when the shackle is moved into the lock-case, a pawl hingedly connected with the bolt so as to be 25 moved thereby to interlock with the heel of the shackle when the bolt moves to interlock with the shackle toe, and means for retaining the bolt and pawl in locking engagement with the shackle, said means being adapted to be actuated to release said bolt and pawl.

5. In a lock, the combination of a lock-case, a shackle mounted to slide in the lock-case, a bolt pivotally mounted in the lock-case and adapted to interlock with the toe of the shackle when 35 the shackle is moved into the lock-case, and means interposed between the bolt and the heel of the shackle and hingedly connected with the bolt for preventing the bolt from moving into its locking position when the shackle is withdrawn 40 from the lock-case.

6. In a lock, the combination of a lock-case, a shackle, a bolt adapted to be moved into locking engagement with the shackle when the shackle is moved into the lock-case, tumbler mechanism 45 having a plurality of gatings which when the gatings are in alinement permit the bolt to be moved to release the shackle and when the gatings are out of alinement hold the bolt in locking engagement with the shackle, a spring arm pivoted on the lock-case and means acting automatically upon movement of the shackle into locking engagement with the bolt for turning said spring arm to actuate said tumbler mechanism to move the gatings out of register. 50

7. In a lock, the combination of a lock-case, a shackle mounted to slide in the lock-case, a bolt adapted to be moved into locking engagement with the shackle when the shackle is moved into the lock-case, tumbler mechanism which when 60 in one position permits the bolt to be moved to release the shackle and when the mechanism is out of said position hold the bolt in locking engagement with the shackle, a shackle-retainer mounted to slide with the shackle during insertion and withdrawal of the shackle, and a device pivoted on the lock-case and actuated by said retainer for moving said tumbler mechanism out of said position when the shackle is moved into locking engagement with the bolt. 65

WILLARD MATHES.
